UNITED STATES PATENT OFFICE

ANTOINE BARNAY, OF PARIS, FRANCE

ARRANGEMENT FOR RECEPTION OF ELECTRIC IMPULSES AND FOR CONTROLLING THE ORIENTATION OF COMMUTATORS

Application filed December 18, 1926, Serial No. 155,745, and in France December 18, 1925. Renewed October 26, 1929.

The present invention has for its object an arrangement for reception of electric impulses and for controlling the orientation of a commutator.

In arrangements of this kind the impulse receiver and the commutator each comprise contacts, the corresponding contacts of the receiver and the commutator being interconnected. The number of receiver contacts is equal to the maximum number of impulses which may constitute a series of impulses.

The object of the invention is to diminish this number of contacts. Thus, in an arrangement contrived to receive ten impulses this invention will permit the reduction to three or four for example of the number of receiver contacts.

The invention is characterized in that each receiver contact is connected to several non-consecutive controlling contacts of the commutator, the consecutive contacts of this commutator being each connected to the contacts actuated successively by the successive impulses and being of a number less than the maximum number of impulses which may constitute a series of impulses.

For example, if the receiver comprises four contacts actuated in the order 1—2—3—4—1—2—3—4—1—2 (for ten impulses) and if the commutator comprises ten controlling contacts I—II—III—IV—V—VI—VII—VIII—IX—X, the contact 1 is connected to the contacts I—V—IX, the 2 contact with the contacts II—VI—X etc.

The accompanying drawing shows by way of example only three embodiments of the invention.

Fig. 1 is a diagram of the principle of the circuits forming the subject of the invention. Fig. 2 is a diagram of the application to a group selector utilized in telephony which may be of a type described in French Patent No. 570,941 and its additions.

Fig. 2^a is a variant of this diagram.

Fig. 3 is a diagram of the application to a line selector of the type described in the said patent.

In Fig. 1 a commutator constituted by the wiper 1 and ten groups of contacts I—X which may be explored by the wiper 1 is set

in operation by a propulsion electro-magnet M.

The circuit of the electro-magnet M is controlled by the contact 2 which is opened on the energization of the relay 3. The said relay 3 brings about by its energization the arrest of the movement of the wiper 1 on one of the contacts I—X; the circuit of this relay is closed by earth, one of the contacts 4—5—6—7, one of the contacts I—X, the wiper 1, the winding of the relay 3 and — battery.

The contacts 4—5—6—7 are closed respectively and periodically by an impulse receiving system (rotary commutator or relay) which responds to the action of trains of electrical impulses; the contact 4 being closed on the first impulse, the contact 5 on the second, the contact 6 on the third, the contact 7 on the fourth, the contact 4 again on the fifth, the contact 5 on the sixth etc., in such wise that one of the contacts 4—5—6—7 alone remains closed at the end of the train of impulses, this contact being determined by the number of impulses sent.

The number of the contacts 4—5—6 or 7 is, in accordance with the invention, always less than the maximum number of impulses which may constitute a train.

The wiper 1 pauses after the contact 4 is opened, after the first impulse, and stops every time the wiper 1 arrives at a contact I—X earthed by way of 4—5—6 and 7.

In order that there may not be a false orientation of the commutator, for a given series of impulses, it is requisite that the wiper 1 should have left the group of contacts previously connected with the group wanted before this group is earthed by the contact 4—5—6 or 7 corresponding to the series in question.

For example, if the number of impulses sent be six, the earth will be connected by way of 5 with the contacts II—VI and X, and, in order that there may not be a false connection, it will suffice that the wiper 1 shall have left the group of contacts II before the earth is reconnected at 5 on the conclusion of the periodical closure of the contacts of the receiver.

Given the speed of the commutator and the incidence of the impulses it will always be possible to determine the number of contacts such as 4—5—6—7 in order that the condition explained above may be fulfilled.

In the selector of Fig. 2 the impulse relay 8 is normally energized when the selector is operative by means which form no part of the subject of the invention. The relay 9 is energized by +earth—10, winding of 9 and —battery. The current impulses sent by a calling station will have for effect to interrupt the circuit of the relay 8 which will be de-energized on each occasion; the slow relay 9 remains held in in spite of the brief interruptions of its circuit at 10.

On the first de-energization of 8 the relay 11 is energized by: 11, 12, 13, 14, 15, 16, 20 17 and closes 4; the earth is connected to the contact groups I, V and IX of the commutator by 18, 19, 4 and at 3 which is energized, across the wiper 1. On the first re-energization of 8 (end of the first impulse) 20 is energized by: +earth, 18, 19, 4, 20 and 11 in series, —battery.

On the second de-energization of 8, 21 is excited by: —battery, 21, 22, 13, 14, 15, 16, 17, +earth; earth is connected to II, VI and X by 18, 23 and 5. On the second re-energization of 8 (end of the second impulse) 24 is energized by: +earth, 18, 23, 5; 24 and 21 in series, —battery.

The relays 11 and 20 have their circuit disconnected at 19 and the electro-magnet M has its circuit closed by: —battery, M, 25, 2, 26, 18 and +earth. The commutator pauses and can thus get the contacts of the group II.

On the third de-energization of 8, 27 is energized by: —battery, 27, 28, 14, 15, 16, 17 and +earth. Earth is connected to the groups III and VII by 6.

On the 3rd re-energization of 8, 29 is energized by: +earth, 18, 30, 6, 29, 27 in series and —battery; 24 and 21 release and earth is cut out at II.

On the 4th de-energization of 8, 31 is energized by: —battery, 31, 32, 15, 16, 17, +earth; earth is connected to IV and VIII by 7. On the 4th re-energization of 8, 33 is excited by: +earth, 18, 34, 7, 33 and 31 in series and —battery; 29 and 27 release and earth is cut out at III.

On the 5th de-energization of 8, II is excited again by: —battery, 11, 12, 35, 16, 17, +earth; earth is cut in at I, V and IX by 4. At this moment, the wiper 1 has already left the group I and can only stop at V. On the 5th re-energization of 8, 20 is re-energized by: +earth, 18, 19, 4, 20 and 11 in series and —battery; 33 and 31 release, and earth is cut out at IV and VIII.

The following de-energizations of 8 and its re-energizations thus act periodically on the relay groups 11—20, 21—24, 27—29, 31—33,

earthing periodically the contacts I—V—IX, II—VI—X, III—VII, IV—VIII. The electro-magnet M, the action of which is controlled by 2, which acts under the influence of the relay 3, is constantly earthed, from the 70 end of the first impulse, by one of the contacts 36, 26, 37 or 38 and 18.

The slow relay 39, energized on the first impulse in parallel with 11, holds until the last impulse, and returns to rest at this instant. When the impulses are terminated, and after the wiper 1 has reached the first contact of the group wanted, the relay 3 is energized in a circuit such as described above and disconnects at 2 the circuit of M, which 80 arrests the wipers.

Two circuits are then completed, one, for actuating the wipers for hunting for an idle line by; +earth 18, a contact such as 38, a contact such as 4, a group of contacts such as V, 40, 41, 25 M and —battery; the other, the test circuit, by: 42, 43, lower winding of 44 test wiper 45 and the pole—on a test contact when this wiper finds an idle line characterized by the presence of this potential on the test contact. The test relay 44 arrests the movement of the wipers by opening the circuit of M at 25.

The remainder of the connecting operations has no relation to the invention.

The definitive de-energization of the relay 8 at the end of the call causes the release of the relay, which opens all the relay circuits in working position.

All the wiper switch devices described in Patent 570,941 and its additions may be utilized, as is understood.

Likewise, the groups of relays 11—20, 21—24, 27—29, 31—34 may be replaced by single double-acting relays.

In Fig. 2^a the groups of lines of the selector are arranged to give the commutator a longer time to move between two series of contacts marked simultaneously by the relays which receive impulses. This arrangement 110 permits, in turn, reduction of the number of these relays.

With this object, the groups of contacts such as I, II etc., in the selector are divided into two parts; one comprising a single contact I, II, III etc. (the first of each group) is normally connected to the corresponding contact actuated by the impulse receiver; it is this contact which determines, by being earthed, the orientation of the wipers of the group selector on the group wanted; the other comprises all the other contacts of the group (I'—II'—III' etc.) normally interconnected and connected to the first contact of their respective group only after the orientation of the wiper actuated by the impulses; these contacts act to permit the hunting for an idle line in the group under consideration.

In this way it will suffice that the wiper 1 has passed beyond the first contact of a group 130

instead of all the contacts of the group as in the preceding case before this group is marked again by the following closure of the corresponding contact such as 4.

It will be easy, referring to the description relative to Fig. 2, to follow the operation of this selector; the only difference resides in the energization of the relay 46 after the end of the series of impulses (release of 39) and after the orientation of the wiper 1 on the group wanted—(energization of 3). The relay 46 is excited by + earth, 42, 47, 46 and — battery; the relay 46 closes the circuit of rotation at 41 and connects, respectively, by 48, 49, 50, 51 the first contacts I, V, IX; II, VI, X; II—VII, IV—VIII of each group to the other contacts I', V'—IX'—II'—VI'—X', III'—VII', IV'—VIII' of these groups.

The line selector of Fig. 3 is oriented by two successive series of impulses each acting on the same set of impulse receiver relays; the first series (tens digit) orients the wiper 1 on the first line of the ten chosen, the second series (units digit) on the line selected in the ten wanted.

On the sending of the first digit, the relay 8 acts on the relays 11—20, 21—24, 27—29, 31—33 as indicated for Fig. 2. On the other hand, as soon as 9 is energized, 52 is energized by; — battery, 52, 53, 16 and + earth. The relay 52 selects the group marking lines on the first contacts of each ten in the commutator by 54, 55, 56 and 57.

The tens I and II, III and IV, V and VI, VII and VIII, IX and X are marked respectively by the same contacts, a commutation relay 58 permitting the choice of one or other wiper set in accordance with the ten demanded as indicated in Patent 570,941.

When the impulses corresponding to the tens digit are terminated, the relay 37 releases, and, according as the number of impulses sent is odd or even, the relays 11 or 27 on the one hand, 21 or 31 on the other hand, are energized, and the relay commutation circuit 58 is closed in the second case only by; + earth, 18, 59, 60, 61 or 62, 58 and — battery. The relay 58 locks up by 63 and 18 and substitutes the set of wipers 65 for 64 by means of 66.

When the wiper 1 reaches the first tens line wanted, the relay 3 is energized as previously described, and opens at 2 the circuit of M. The holding circuit of the relays 11, 20, 21, 24, 27, 29, 31, 33 kept closed until now, either by 67 (during the impulses) or by 68 (until the orientation of 1) is then opened and these relays release. The relay 69 earthed by: 18, 67, 70 is short-circuited until all the relays which receive impulses release by: + earth, 18, 71, 72 and one of the contacts 73 to 76, 77. This short-circuit is broken at 73, 74, 75 or 76 when the relay 33, 29, 24 or 20 releases and 69 is energized; 69 is locked up by 18 and 79 and prevents a new short-circuit by the open-

ing of 77. The relay 3 remains locked up until now by: + earth, 18, 71, 72 and 78. The relay 52 has its circuit opened at 53, and switches the marking lines on to the units control contacts by: 80, 81, 82, 83. Further, the tens control contacts are connected to the units marking line 1 by 84 and 85.

The second digit acts in the same manner as the first and at the end of the definitive orientation 39 is at rest and 3 at work.

A test circuit is closed by: + earth, 18, 86, a contact such as 38, 87, 88, 89, 90, the two windings of the test relay 91, 66, wiper 65 and test contact of the line called. A circuit for the relay 92 is closed by: + earth, 18, 71, 72, a contact such as 73, 93, 92 and — battery. If the line is idle, the relay finds the pole on its test contact, is energized and is locked by 94 and its upper winding before its circuit is interrupted at 90 by the slow relay 92. If the called line is busy, 91, is shunted by the plus polarity on the test contact and 92 is alone energized giving, for example, the busy tone.

What I claim as new and desire to secure by Letters Patent of the United States is:—

1. In a selector switch operated by electrical impulses, an impulse receiving device comprising setting contacts, the number of the said contacts being smaller than the maximum number of impulses in a series of impulses, a connecting switch provided with control contacts, means for connecting each of the setting contacts of the impulse receiving device to several non-consecutive control contacts, and means for connecting the intermediate control contacts of the said connecting switch to the successive setting contacts of the impulse receiving device.

2. In a selector switch operated by electrical impulses, an impulse receiving device comprising relays the number of which is smaller than the maximum number of impulses in a series of impulses, each relay being arranged to operate a setting contact, a connecting switch provided with control contact means for connecting each of the setting contacts to several non-consecutive control contacts, means for successively connecting the intermediate control contacts to the successive setting contacts, means for successively and periodically energizing relays according to the successive impulses of a series.

3. In a selector switch operated by electrical impulses, an impulse receiving device comprising relays the number of which is smaller than the maximum number of impulses in a series of impulses, each relay being arranged to operate a setting contact, a connecting switch provided with a group of control contacts, means for connecting each of the setting contacts to several non-consecutive groups of control contacts, means for successively energizing relays according to the successive impulses of a series.

4. In a selector switch operated by electrical impulses, an impulse receiving device comprising setting contacts, the number of which is smaller than the maximum number of impulses in a series of impulses, a connecting switch provided with groups of control contacts, means for connecting, when receiving the impulses, each of the setting contacts to the first contact of several non-consecutive groups of control contacts, and means for respectively connecting, after receiving the impulses, the remaining contacts of the groups of control contacts to the setting contacts.
5. In a selector switch operated by electrical impulses, an impulse receiving device arranged to receive two different series of impulses and comprising setting contacts the number of which is smaller than the maximum number of impulses of a series of impulses, a connecting switch provided with groups of control contacts, each group being divided into sub-groups, means for connecting, during the first series of impulses, each of the setting contacts to the first contact of several non-consecutive groups of control contacts, means for connecting, during the second series of impulses, each of the setting contacts to several non-consecutive control contacts in each of the sub-group.
- 30 In testimony whereof I have signed my name to this specification.

ANTOINE BARNAY.
